UNITED STATES PATENT OFFICE.

WILLIAM F. MORTON, OF NEW HAVEN, CONNECTICUT, ASSIGNOR OF ONE-HALF TO HOLCOMB BROTHERS & CO., OF SAME PLACE.

MACHINE FOR COMPRESSING TENONS.

SPECIFICATION forming part of Letters Patent No. 380,727, dated April 10, 1888.

Application filed April 23, 1887. Serial No. 235,835. (No model.)

To all whom it may concern:

Be it known that I, WILLIAM F. MORTON, residing at New Haven, in the county of New Haven and State of Connecticut, have invented 5 certain new and useful Improvements in Machines for Compressing Tenons; and I do declare the following to be a full, clear, and exact description of the same, reference being had to the accompanying drawings, which form a part 10 of this specification.

My invention relates to an improved machine for forming compressed spoke-tenons from suitable tenon-blanks, the object being 15 to produce a machine adapted to do its work without injuring the fibers of the wood and without producing a burr upon the resultant tenon, adjustable to the production of tenons of different sizes, having a large capacity for work, and of simple, cheap, and durable construction.

With these ends in view my invention consists in a machine having dies adapted to completely inclose the tenon-blank from the beginning to the end of the compressing operation and to simultaneously compress it in two 25 diametrically-opposite directions.

My invention further consists in certain details of construction and combinations of parts, as will be hereinafter described, and pointed 30 out in the claims.

In the accompanying drawings, Figure 1 is a view in front elevation of a machine embodying my invention. Fig. 2 is a plan view thereof, with the operating-lever and the uprights 35 of the press in transverse section. Fig. 3 is a view of the machine in vertical longitudinal section on the line *a b* of Fig. 1, and looking toward the stationary edge die. Fig. 4 is an enlarged broken view in vertical transverse 40 section on the line *c d* of Fig. 2. Fig. 5 is a detached reverse plan view of the stationary edge die. Fig. 6 is a detached plan view of the clamping-block. Fig. 7 is an enlarged detached plan view of the movable beveled side 45 die, the spring thereof, and the die-block, such parts being connected together. Fig. 8 is a similar detached plan view of such die. Fig. 9 is a similar view of the die-block. Fig. 10 is a similar view of the spring. Fig. 11 is an enlarged 50 view in elevation of the movable edge die and the carrier and the spring-retaining block

thereof. Fig. 12 is a similar view of the carrier with the said edge die removed. Fig. 13 is a similar detached view in reverse elevation of the movable edge die. Fig. 14 is a similar detached 55 view of the spring thereof. Fig. 15 is a similar detached plan view of the spring-retaining block. Fig. 16 is a broken view in side elevation of a spoke having a tenon-blank. Fig. 17 is a similar edge view of the spoke and the 60 blank. Fig. 18 is an end view of the spoke and blank. Fig. 19 is a side view of the spoke, showing the compressed tenon produced under my invention. Fig. 20 is an edge view of such spoke and tenon, and Fig. 21 is an end 65 view thereof.

My improved machine, as herein shown, is provided with side dies, A and B, and edge dies, C and D, such dies being grouped to inclose a tenon-blank, E, gradually widening, 70 both edgewise and flatwise, from its inner to its outer end, as shown by Figs. 16, 17, and 18 of the drawings, and compressed by the dies mentioned to form a tenon having flat sides 75 F F, a flat face, G, and a tapering back, H, as shown by Figs. 19, 20, and 21 of the drawings.

The side die, A, is horizontally movable and normally exposes a working-surface of sufficient area to completely cover one side of any blank, such working surface being ribbed or 80 corrugated, so as to indent that side of the blank which is in contact with it, and thus increase the capacity of the tenon for holding glue. The inner end, I, of the die is beveled to conform to the taper of the back H of the 85 tenon. Its outer end is cut away, as at J, (see Figs. 4, 7, and 8,) to receive the spring K, as shown. An adjustable die-block, L, also having its inner end beveled to conform to the taper of the back H of the tenon, supports the 90 said die A, the two parts being dovetailed together, (see Fig. 3,) so as to permit the die to move freely upon the die-block. Slots N N, located at the rear end of the die-block, receive the opposite ends of the spring K, which pushes 95 the die A inward, so that its beveled end normally overhangs the beveled end of the die-block. A screw, O, (see Fig. 4,) entering the die-block from the lower face thereof, extends into the elongated slot P, formed in the lower 100 face of the die, and limits the sliding movement of the same.

The stationary edge die, C, forming the face G of the tenon, is provided with a flat working-face, Q, and with a guiding-extension, R, projecting forward and aiding in the introduction of the blanks between the dies, and forming a bearing for and thus protecting the adjacent shoulder of the two shoulders S S (see Figs. 16 to 21, inclusive) of the spoke T. A longitudinal recess, U, formed in the lower face of the die C, adapts it to set over the die A, so as to clear the same and to rest upon the projecting edges of the die-block L, as clearly shown by Fig. 3 of the drawings, whereby the said side die is left free to move back and forth in the recess. Also, by setting the die C over the die A and resting the former upon the die-block L, the said parts are coupled together as against relative lateral displacement. The said die C is also provided at its outer end with a vertical opening, V, as shown.

A clamping-block, W, provided with an extension, X, and with an upright threaded stud, Y, which is carried by such extension, is secured to the bed Z of the press to which the invention is applied, the said extension X entering the outer end of the recess U in the die C, and the stud Y passing upward through the opening V (see Figs. 4 and 5) in the rear of the die. A nut, A', applied to the projecting upper end of the said stud Y, screws down upon the upper face of the die C and clamps the same and the die-block together, and both to the bed of the press. The described construction adapts the side die, A, the edge die, C, and the die-block L to be vertically adjusted by means to be hereinafter described.

The movable edge die, D, forming the tapering back H of the tenon, is provided upon its inner face with an elongated horizontal slot, B', and an open recess, C', parallel therewith, and upon its forward edge with a finger, D', forming a bearing for the adjacent shoulder of the spoke. This die is mounted for free vertical movement and at an angle conforming to the bevel of the inner ends of the die A and the die-block L upon the inner end of a carrier, E', the two parts being dovetailed together, as shown by Fig. 2 of the drawings. A spring, F', located in the recess C' aforesaid, normally supports the die D in a position of sufficient elevation above the working-face of the die A to expose a working-face of sufficient area to completely cover one edge of any tenon-blank. A retaining-block, G', having its inner edge slotted to form the horizontal shoulders H' and I', is secured by a screw, J', in a recess, K', formed in the inner end of the said carrier E', as shown by Fig. 4 of the drawings. The shoulder H' of this block enters the slot B' in the rear face of the die D, which is limited in the range of its vertical movement by the engagement of the upper and lower walls of such slot with the said shoulder, while the shoulder I' of the said block enters the recess C' of the die and supports the spring F' in place.

The side die, B, effects the flatwise compres-

sion of the blank. It is adapted in the area of its working-face to cover one side of any tenon-blank, such face being ribbed or corrugated to indent the blank to increase the capacity of the resultant tenon for retaining glue. It works against the working-face of the stationary edge die, C, and engages with the upper edge of the movable edge die, D, which it retires against the spring F' to expose the blank for flatwise compression. It is secured to the gate L' of the press, whereby it is reciprocated and advanced upon the blank.

The edgewise compression of the blank is effected by the movable edge die, D, the carrier E' of which is attached to a carrier, M', sliding horizontally in a groove, N', formed in the bed of the press, and attached by a link, O', to an upright operating-lever, P', actuated by the engagement of its upper end with a cam, Q', mounted upon the shaft R' of the press, the lower end of such lever being fulcrumed to a rod, S', passing horizontally through the bed of the press and through a wheel, T', by which it is adjusted back and forth to regulate and conform the throw of the carriage to the adjustment of the die-block L. A movable bed, U', supporting the said die-block, and hence the dies A and C, is mounted transversely in the bed of the machine and provided with an inclined under face, V', bearing upon a similar face, W', therein, the said bed being also provided with a threaded stem, X', passing through a threaded sleeve, Y', mounted in bearings Z' and turned to advance or retract the bed U' by a hand-wheel, A², all as shown by Figs. 2 and 3 of the drawings.

Figs. 16 to 21, inclusive, illustrate the work of the machine. The blank shown is wedge-shaped in form and gradually widens both edgewise and flatwise from its inner to its outer end. The tenon formed from such blank has flat indented sides, a flat face constituting its forward edge and a taper back constituting its rear edge. Its tendency is to resume its blank form, and this it will do in a measure after it has been driven, with the obvious result of locking the spoke in the hub.

Having described the machine in detail, I will now set forth its operation.

In the first place the dies are adjusted to the work to be done. For thin tenon-blanks the nut A' is unscrewed and the movable bed U' is retracted, whereby the die-block L and the dies A and C will be elevated. For thick blanks the said bed is moved forward, permitting the said die-block and dies to drop to a lower level. For narrow blanks, the die-block L, and hence the die A, which is connected with it, are moved inward or toward the die D, and hence transversely on the movable bed, while for wide blanks the die-block and the die A are moved outward and away from the said die D. After the dies have been set, as described, the nut A' is screwed down upon the die C, whereby the die-block L and the die C are clamped together and to the bed

of the press. The throw of the carriage E' is then regulated so that in its forward movement it will advance the die D to the beveled edge of the die-block. When the dies are set 5 ready to compress a tenon-blank, they will completely inclose it, the overhanging inner edge of the die A taking in the excess in the width of the blank over the width of the tenon to be formed from it, and the extension of the 10 die D above the face of the die A taking in the thickness of the blank over the thickness of the said resultant tenon. When the press is operated, the die B descends vertically for the flatwise compression of the blank and the 15 die D simultaneously advances horizontally for the edgewise compression thereof, the die B striking the die D and pushing the same downward to expose the blank for flatwise compression, and the die D engaging with the 20 die A and pushing it outward to expose the blank for edgewise compression. The retirement of the dies D and A, as described, for the exposure of the blank, is effected in pace with the progression of the compression thereof, 25 whereby the blank is perfectly confined from the beginning to the end of the operation, and so condensed without any of the strain upon its fibers which results when a blank is compressed under only partial confinement, and 30 due to a crowding of the fibers toward the point where there is relief from pressure. Such crowding of the fibers is avoided by completely confining the blank during its compression and applying that compression in 35 two diametrically-opposite directions simultaneously.

It is obvious that with my improved machine no burr is produced upon the resultant tenon, which is hardened and reduced in size 40 without in any way injuring or impairing the life of its fibers, which are compacted without other disturbance than that of being brought into closer relations. The described capacity for adjustment adapts the machine to be set 45 for the compression of blanks of all of the ordinary sizes. The machine may be operated with great rapidity with uniformly good results.

It is apparent that the machine may not always 50 take the form herein shown and described, and I would therefore have it understood that I do not limit myself to such form, but hold myself at liberty to make such changes and alterations as fairly fall within 55 the spirit and scope of my invention.

The tenon and tenon-blank described herein have been made the subject of another application, filed April 23, 1887, No. 235,836, and 60 no claim to such tenon or tenon-blank is relinquished herein.

Having fully described my invention, what I claim as new, and desire to secure by Letters Patent, is—

1. In a machine for forming compressed 65 tenons, the combination, with a movable die adapted to be advanced in one direction to

compress a tenon-blank and to be retired in another direction to expose such blank for compression, of dies co-operating with such movable die to completely inclose and compress the blank, substantially as set forth. 70

2. In a machine for forming compressed tenons, the combination, with a movable edge die retiring to expose the blank for flatwise compression, of a movable side die retiring to expose the blank for edgewise compression, and dies co-operating with such dies to completely inclose and to compress the blank, substantially as set forth. 75

3. In a machine for forming compressed tenons, the combination, with a side die and an edge die adapted to be retired in pace with the compression of a tenon-blank to expose the same for such compression, of dies co-operating with such retiring dies to completely 85 inclose the blank from the beginning to the end of the compressing operation, substantially as set forth. 80

4. In a machine for forming compressed tenons, the combination, with dies covering 90 the sides and one edge of a tenon-blank, of an adjustable die to cover the other edge of the blank, which is thus completely covered by the dies, substantially as set forth.

5. In a machine for forming compressed tenons, the combination, with dies covering 95 the edges and one side of a tenon-blank, of an adjustable die for covering the other side of the blank, which is thus completely inclosed by the dies, substantially as set forth. 100

6. In a machine for forming compressed tenons, the combination, with an adjustable side die and an adjustable edge die, of dies co-operating with such dies to completely inclose and to compress a tenon blank, substantially 105 as set forth.

7. In a machine for forming compressed tenons, the combination, with a positively-moved edge die and a positively-moved side die, of dies co-operating therewith to completely inclose a tenon-blank which is gradually exposed for compression by the retirement of two of the dies, substantially as set forth. 110

8. In a machine for forming compressed tenons, the combination, with a retiring side die and a retiring edge die, of springs for maintaining such dies in their normal positions, and one or more dies co-operating with such retiring dies to completely cover and to compress a tenon-blank, substantially as set forth. 115

9. In a machine for forming compressed tenons, the combination, with a positively-moved die, of a retiring die engaged and retired thereby, and one or more dies co-operating with those mentioned to completely inclose and to compress a tenon blank, substantially as set forth. 125

10. In a machine for forming compressed tenons, the combination, with a positively-moved edge die, of a retiring side die engaged 130

and retired thereby, and one or more dies co-operating with those mentioned to completely inclose and to compress a tenon-blank, substantially as set forth.

5 11. In a machine for forming compressed tenons, the combination, with a positively-moved side die, of a retiring edge die engaged and retired thereby, and one or more dies co-operating with such dies to completely inclose 10 and to compress a tenon-blank, substantially as set forth.

12. In a machine for forming compressed tenons, the combination, with a retiring side die, of a die-block located below the said die, 15 which normally hangs over its inner end, and two or more dies co-operating with such die to completely cover and to compress a tenon-blank, substantially as set forth.

13. In a machine for forming compressed tenons, the combination, with a retiring side die, of an adjustable die-block located below it, means for holding the said block in its adjustment, and two or more dies co-operating with the said die to completely cover and to 25 compress a tenon-blank, substantially as set forth.

14. In a machine for forming compressed tenons, the combination, with a retiring side die, of a normally stationary edge die, a die-block located below the side die and supporting the edge die to permit the free movement 30 of the side die between them, and two or more dies co-operating with such dies to completely inclose a tenon-blank, substantially as set forth.

15. In a machine for forming compressed tenons, the combination, with a retiring side die, of a die-block located below it and two or 40 more dies co-operating with such die to completely cover a tenon-blank, the said side die and block being connected together for a free movement of the former upon the latter, substantially as set forth.

16. In a machine for forming compressed tenons, the combination, with a retiring side die, of a die-block located below and co-operating with it, a spring for the die, means for 45 limiting the movement of the die under the action of the spring, and two or more dies co-operating with the said die to completely cover a tenon-blank, the said die and block being loosely dovetailed together, substantially as set forth.

17. In a machine for forming compressed tenons, the combination, with a retiring side die, of a stationary edge die having a horizontal recess in its lower face, a clamping-block entering the outer end of such recess and carrying an upright stud passing through the said 50 die, which is thereby clamped in place, and one or more dies co-operating with the dies mentioned in completely covering a tenon-blank, substantially as set forth.

18. In a machine for forming compressed tenons, the combination, with a retiring side die having a beveled end, of a positively-

70 moved edge die conforming to the beveled edge of the side die, and one or more dies co-operating with such dies to completely inclose a tenon-blank, substantially as set forth.

19. In a machine for forming compressed tenons, the combination, with a retiring side die having a beveled end, of a die-block located below it and having its inner end beveled to conform to the bevel of the die, a positively-moved edge die conforming to the bevel of the said die and block and co-operating with them, and one or more dies co-operating with such dies to completely inclose and compress a tenon-blank, substantially as set forth. 80

20. In a machine for forming compressed tenons, the combination, with a positively-moved carrier, of a die mounted thereupon so as to move independently of the motion it has therewith, and dies co-operating with such die to completely cover and to compress a tenon-blank, substantially as set forth. 85

21. In a machine for forming compressed tenons, the combination, with a positively-moved carrier, of an edge die movably mounted 90 thereupon, a positively-moved side die engaging with the said edge die and moving it upon the carrier independent of the motion it has therewith, and dies co-operating with such dies to completely cover and compress a tenon-blank, substantially as set forth. 95

22. In a machine for forming compressed tenons, the combination, with a positively-moved carrier, of a movable edge die mounted thereupon, a spring for such die, a stop for 100 limiting the play of the die upon the carrier, and dies co-operating with such die to completely cover and to compress a tenon-blank, substantially as set forth.

23. In a machine for forming compressed tenons, the combination, with a positively-moved carrier, of a movable edge die mounted thereupon, a spring for such die, a retaining-block secured to the carrier and retaining the spring in place and limiting the movement of 105 the die upon the carrier, and dies co-operating with such die to completely inclose and to compress a tenon-blank, substantially as set forth. 110

24. In a machine for forming compressed tenons, the combination, with side and edge 115 dies adapted to completely inclose a tenon-blank and to compress the same, for which purpose one or more of the dies are retired, of a forward guiding-extension co-operating with the dies, substantially as set forth. 120

25. In a machine for forming compressed tenons, the combination, with a stationary edge die having a forward guiding-extension, of dies co-operating with such die in completely inclosing a tenon-blank, substantially 125 as set forth.

26. In a machine for forming compressed tenons, the combination, with dies adapted to inclose a tenon-blank, of bearings for supporting and protecting the parts of the blank adjacent to the parts thereof subjected to compression, substantially as set forth. 130

27. In a machine for forming compressed tenons, the combination, with an edge die positively moved for the edgewise compression of a tenon-blank, of means for adjusting the compressing action of such die, and dies co-operating with the said die to completely inclose and to compress the blank, substantially as set forth.
28. In a machine for forming compressed tenons, the combination, with a retiring side die and a positively-moved side die, of means for adjusting the former die toward and away from the latter die, and dies co-operating with such dies to completely inclose and to compress a tenon-blank, substantially as set forth.
29. In a machine for forming compressed tenons, the combination, with a movable side die, of a normally stationary edge die, a movable edge die effecting the edgewise compression of a tenon-blank and the retirement of the movable side die to expose the blank for such compression, and a side die effecting the flatwise compression of the blank and the retirement of the movable side die to expose the blank for such compression, substantially as set forth.
30. In a machine for forming compressed tenons from a tenon-blank, the combination, with a beveled movable side die, of a normally stationary edge die, a movable edge die conforming to the bevel of the side die and effecting the edgewise compression of the blank and the retirement of the movable side die to expose the blank for such compression, a side die effecting the flatwise compression of the blank and the retirement of the movable edge die to expose the blank for such compression, and a beveled die-block located below the movable side die, substantially as set forth.

In testimony whereof I have signed this specification in the presence of two subscribing witnesses.

WILLIAM F. MORTON.
